UNITED STATES PATENT OFFICE

2,100,881

SIGNAL SYSTEM

Chauncey G. Suits, Schenectady, N. Y., assignor
to General Electric Company, a corporation
of New York

Application March 12, 1936, Serial No. 68,405

13 Claims. (Cl. 246—39)

My invention relates to railway block signal systems and one of its objects is to provide an improved electrically operated signal system, whereby the signals may be more satisfactorily and reliably controlled than has been possible heretofore.

In the usual form of signal system, means are provided whereby the signal or signals at the entrance of a block which is occupied by a vehicle are caused to indicate "danger", and the signal or signals at the entrance of the block at the rear of the vehicle are caused to indicate "caution", the latter indication being frequently dependent upon the presence of a following vehicle in the second block to the rear.

The value of a signal system depends, of course, upon the reliability of the system under all circumstances and under all possible types of failure. For example, when a lamp burns out the indication given must be in the progressively safe direction. Any type of failure which causes two lamps to be lighted simultaneously in the same block is considered bad because of the psychological effect upon the engineer. It should be understood that in railway practice a very dangerous signal is given to the engineer when no lamp in a block is lighted since the engineer interprets this condition to mean that the signal system is out of order and may fail, therefore, to indicate a hazardous situation. It is, therefore, an object of my invention to provide an improved railway signal system which satisfies the above safety requirements.

It is a further object of my invention to provide a railway signal control system which may de-energize a signal lamp by supplying a current thereto which is of like magnitude but opposite phase to the current normally flowing through the lamp.

It is a still further object of my invention to provide an improved type of saturable reactor which increases the reliability of performance of a railway signal system.

The novel features which I believe to be characteristic of my invention are set forth with particularity in the appended claims. My invention itself, however, both as to its organization and method of operation together with further objects and advantages thereof may best be understood by reference to the following description taken in connection with the accompanying drawing, the single figure of which diagrammatically illustrates one embodiment of my invention.

Referring to the single figure of the drawing, I have represented at 1 one track of a two track railway system. This track is divided into blocks A, B, C, etc. in accordance with common practice, the rails of the different blocks being electrically insulated from each other as is indicated at the

points 2 and 3. At 4, 5, and 6 I have indicated the signaling equipments which are associated with each of the blocks A, B, and C, respectively. These equipments are all identical in circuit arrangement and it will be understood that similar equipment is associated with each of the different blocks of the railway system, and that in the interests of clarity, only equipment 5 is shown in detail.

While any suitable system of signals may be employed in equipments 4, 5, and 6, I have shown a plurality of lamps which indicate different track conditions when selectively lighted. For example, when the lamp R is energized, the occupied condition of the block B or "danger" is indicated. When the lamp Y is energized, the occupied condition of the adjacent block in the direction of traffic or "caution" is indicated and when the lamp G is energized for "clear" or "safe" the condition of both of the above mentioned blocks is indicated.

I have indicated at 7 a power supply circuit which is normally energized from a source 8 and which may extend throughout the railway system. Energy from the supply circuit 7 is supplied through transformers 9, 10, and 11 to signaling equipments 4, 5, and 6, respectively.

Track circuit equipment for blocks A, B, and C is indicated conventionally at 12, 13 and 14. Any of the standard types of track circuits may be used and since the track circuit forms no part of this invention the circuit is illustrated diagrammatically by a rectangle. It will be understood that the track circuit supplies a direct current to the signal equipment only when the block with which it is associated is in an unoccupied condition.

Referring to signaling equipment 5 which I have illustrated in detail in the drawing, it will be noted that the lamp circuits of signal lamps R, Y and G are connected in parallel to the secondary winding of transformer 10. In order selectively to control the flow of current through the different lamp circuits two saturable reactors 15 and 16 are provided in series in the "caution" lamp circuit and the "clear" lamp circuit respectively. Saturable reactor 15 is provided with a direct current winding 17 which determines the degree of saturation of reactor 15 and hence the flow of current through the alternating current winding 18. When direct current is flowing through winding 17, alternating current from supply line 7 will flow through winding 18. Saturable reactor 16 is provided with a direct current winding 19 and an alternating current winding 20, and operates in a manner similar to that of reactor 15 to control the flow of current through the "clear" lamp circuit. Since winding 17 of reactor 15 is connected to track circuit

13 of block B, it will be understood that reactor 15 will remain saturated and hence will permit current flow through winding 18 as long as block B remains in an unoccupied condition. Similarly, 5 since winding 19 is connected to track circuit 14 of block C, reactor 16 will remain saturated and hence will permit current flow through winding 20 as long as block C remains in an unoccupied condition.

10 A novel means is provided for turning off the "danger" lamp R when current is flowing through the "caution" lamp circuit and for turning off the "caution" lamp Y when current is flowing through the "clear" lamp circuit. A transformer 21 having its primary connected in series in the "caution" lamp circuit and its secondary connected in shunt to "danger" lamp R supplies a current of like magnitude but opposite phase to that normally flowing through "danger" lamp R when current is flowing through the "caution" lamp circuit. A transformer 22 having its primary connected in series in the "clear" lamp circuit and its secondary connected in shunt to "caution" lamp Y supplies a current of like magnitude but opposite phase to that normally flowing through "caution" lamp Y when current is flowing through the "clear" lamp circuit.

15 In order to prevent current flow in the "clear" lamp circuit when no current is flowing in the "caution" lamp circuit a saturable reactor 23 is provided having its alternating current winding 24 connected in series in the "clear" lamp circuit. The direct current winding 25 of reactor 23 is connected through a suitable rectifying device 26 to an auto-transformer 27 connected in series in the "caution" lamp circuit. Consequently, reactor 23 will be saturated only when current is flowing through the "caution" lamp circuit. Similarly, a reactor 28 is provided having its alternating current winding 29 connected in series in the "caution" lamp circuit and its direct current winding connected through a rectifying device 30 to an auto-transformer 31 connected in series in the "danger" lamp circuit.

20 45 A ballast reactor 32 may be provided in series in the "danger" lamp circuit if desired. In order to provide the same voltage drop across "danger" lamp R as is applied across "caution" lamp Y and "clear" lamp G, one side of the "danger" lamp circuit is connected to an intermediate point 33 on the secondary of transformer 10, rather than to the end point.

25 50 The normal operation of my device is as follows: When both blocks B and C are in an unoccupied condition, current flows through all three of the parallel lamp circuits but only the "clear" lamp G will be energized since current supplied from transformers 21 and 22 causes de-energization of "danger" lamp R and "caution" lamp Y respectively. If block C be occupied and block B unoccupied, reactor 16 will be unsaturated and no current will flow through the "clear" lamp circuit. Since current flows through the "caution" lamp circuit, "caution" lamp Y will be energized but "danger" lamp R will be deenergized because of current supplied thereto from transformer 21. If block B be occupied and block C unoccupied reactor 15 will not be saturated and hence no current will flow through the "caution" lamp circuit. Since no current flows in the "caution" lamp circuit no direct current will be supplied from rectifying device 26 to direct current winding 25 of reactor 23 hence no current will flow through the "clear" lamp

25 30 circuit. Therefore, under these circumstances "danger" lamp R will be energized and "caution" lamp Y and "clear" lamp G will be deenergized.

35 40 In order to improve the reliability of performance under various types of failure, a novel construction has been adopted for saturable reactors 15 and 16. The alternating current winding in the usual form of saturable reactor consists of two coils which are normally operated in parallel. A short circuit of either one of these coils is a possible type of failure which may result in a "dangerous" indication. Reactors 15 and 16 preferably are constructed in such a way that the alternating current winding is made up 15 of a plurality of separate coils. For example, alternating current winding 18 of reactor 15 is made up of a plurality of separate coils 18a, 18b, and 18c connected in series and so arranged that a short circuit of any one coil will not interrupt 20 the normal operation of the circuit. In order to improve the reactance ratio that is available in control reactors 15 and 16 I prefer to construct these reactors with tertiary windings 34 and 35 respectively which have a plurality of condensers 25 36 and 37 connected in shunt across them.

45 50 Considering now various possible types of failure it will be observed that the most common type of failure, namely, a lamp "burn out" causes the next most restrictive signal to be given. When, for example, the green light burns out, the yellow light is automatically turned on, since this obviously is preferable to no light at all. Similarly, when the yellow light burns out, the red light is automatically turned on. The following tables give various other possible types of failure and indicate the result:

Case I.—Green light on

Possible failure	Result		
	R	Y	G
Reactor 16 Normal operation	Off	Off	On
(a) Open d-c winding.....	Off	On	Off
(b) Short d-c winding.....	Off	On	Off
(c) Short any section of a-c winding.....	Off	Off	On
(d) Open any section of a-c winding.....	Off	On	Off
(e) Short either condenser.....	Off	Off	On
(f) Open either condenser.....	Off	Dim	Off
Reactor 15 Normal operation	Off	Off	On
(a) Open d-c winding.....	On	Off	Off

	(b) Short top side	On	Off	Off
	(c) Open bottom side	On	Off	Off
	(d) Short bottom side	Dim	Off	Off

It will readily be observed from the above tables that under any possible failure the indi-

cation will be either the same as under normal operation or will be more restrictive to traffic.

While I have shown a particular embodiment of my invention, it will of course be understood that I do not wish to be limited thereto since many modifications may be made both in the circuit arrangement and the instrumentalities employed and I contemplate by the appended claims to cover all such modifications as fall within the true spirit and scope of my invention.

What I claim as new and desire to secure by Letters Patent of the United States, is:—

1. The combination comprising a plurality of signals, means for de-energizing one of said signals by current supplied from the energizing circuit of a second of said signals, and additional means for de-energizing said second signal when the normal energizing circuit of said first signal is broken.

2. The combination comprising a source of current, a plurality of electrically operable signals connected in parallel to said source, means for selectively energizing said signals, a saturable reactor in one of said circuits, and means operable in response to a flow of current in a second one of said circuits for saturating said reactor.

3. In a railway signal circuit, the combination comprising a source of alternating current, a plurality of signals, including clear, caution, and danger signals having their energizing circuits connected in parallel to said source, means for selectively de-energizing said caution signal circuit and said clear signal circuit, means operative when current is flowing through said caution signal circuit for supplying a current to said danger signal which is of like magnitude and opposite phase to that normally flowing through the energizing circuit of said danger signal, and means operative when current is flowing through said clear signal circuit for supplying a current to said caution signal which is of like magnitude and opposite phase to that normally flowing through the energizing circuit of said caution signal.

4. In a railway signal circuit, the combination comprising a source of alternating current, a plurality of signal lamps, including clear, caution, and danger lamps connected in parallel circuits to said source, means for selectively de-energizing said caution lamp circuit and said clear lamp circuit, means operative when current is flowing through said caution lamp circuit for supplying a current through said danger lamp which is of like magnitude and opposite phase to that normally flowing through said danger lamp, and means operative when current is flowing through said clear lamp circuit for supplying a current through said caution lamp which is of like magnitude and opposite phase to that normally flowing through said caution lamp, and means for rendering a lamp circuit inoperative when there is a current failure in the circuit of a lamp indicating a more dangerous condition.

5. In a railway signal circuit, the combination comprising a source of alternating current, a plurality of signals, including clear, caution, and danger signals whose energizing circuits are connected in parallel to said source, means including a plurality of saturable reactors for selectively de-energizing said caution signal circuit and said clear signal circuit, means operative when current is flowing through said caution signal circuit for superimposing a current on the

- energizing current of said danger signal which is of like magnitude but opposite phase to the normal energizing current of said danger signal, and means operative when current is flowing through said clear signal circuit for superimposing a current on the energizing circuit of said caution signal which is of like magnitude but opposite phase to the normal energizing circuit of said caution signal.
10. In a railway signal circuit, the combination comprising a source of current, a plurality of signals including clear, caution, and danger signals connected in parallel circuits to said source, means for selectively energizing said signals according to track conditions, a saturable reactor in said clear signal circuit, means in said caution signal circuit for saturating said reactor when current is flowing through said caution signal circuit, a second saturable reactor in said 20 caution signal circuit, and means in said danger signal circuit for saturating said second reactor when current is flowing through said danger signal circuit.
7. In a railway signal circuit, the combination comprising a source of alternating current, a plurality of signal lamps, including clear, caution, and danger lamps connected in parallel circuits to said source, means for selectively de-energizing said caution lamp circuit and said clear lamp circuit, means operative when current is flowing through said caution lamp circuit for supplying a current through said danger lamp which is of like magnitude and opposite phase to that normally flowing through said danger lamp, means operative when current is flowing through said clear lamp circuit for supplying a current through said caution lamp which is of like magnitude and opposite phase to that normally flowing through said caution lamp, a saturable reactor in said clear lamp circuit, means in said caution lamp circuit for saturating said reactor when current is flowing through said caution lamp circuit, and means in said danger lamp circuit for saturating said second reactor when current is flowing through said danger lamp circuit.
8. In a railway block signal system, the combination comprising a section of railway track divided into three blocks, a source of alternating current, a plurality of signal lamps in each block including clear, caution, and danger lamps connected in parallel circuits to said source, means operative when current is flowing through the caution lamp circuit of a block for supplying current through the danger lamp of the same block which is of like magnitude and opposite phase to that normally flowing through said danger lamp, means operative when current is flowing through the clear lamp circuit of a block for supplying a current through the caution lamp circuit of the same block of like magnitude and opposite phase to that normally flowing through said caution lamp, saturable reactors in said caution lamp circuits and said clear lamp circuits, means in said second block for controlling the degree of saturation of the saturable reactor in the clear lamp circuit of said second block,

and means associated with said third block for controlling the degree of saturation of the saturable reactor in the clear lamp circuit of said second block.

9. In a railway track signal circuit, the combination comprising a source of alternating current, a plurality of signal lamps in each block including clear, caution, and danger lamps connected in parallel circuits to said source, means including a plurality of saturable control reactors for selectively energizing said lamps according to track conditions, a saturable safety reactor in said clear lamp circuit, means in said caution lamp circuit for saturating said safety reactor when current is flowing through said caution lamp circuit, a second saturable safety reactor in said caution lamp circuit, and means in said danger lamp circuit for saturating said second safety reactor when current is flowing through said danger lamp circuit, each of said reactors being provided with a sectionalized alternating current winding thereby to prevent a layer to layer short circuit or a turn to turn short circuit from affecting the normal operation of the signalling system.

10. The combination comprising a source of current, a plurality of signals connected in parallel thereto, means for deenergizing one of said signals in response to current in the circuit of another of said signals and means comprising a saturable reactor in said circuit for controlling the signal therein in accordance with the current in the circuit of said one signal.

11. The combination comprising a source of current, a plurality of circuits connected in parallel to said source, a signal in each of said circuits, means for deenergizing the signal in one of said circuits by the current in another of said circuits and means comprising a saturable reactor in said other circuit for deenergizing the signal therein in response to an opening of said one circuit.

12. The combination comprising a source of current, a plurality of circuits connected in parallel to said source, a signal in each of said circuits, saturable reactor means in said circuits for selectively energizing said signals, means responsive to the current in one of said circuits for deenergizing the signal in another of said circuits and means including a saturable reactor in said one circuit and controlled by the current in said other circuit for deenergizing the signal in said one circuit.

13. The combination comprising a source of current, a plurality of circuits connected in parallel to said source, a signal in each of said circuits, means including a saturable reactor in each of said circuits for selectively energizing said signals, means responsive to the current in one of said circuits for deenergizing the signal in another of said circuits, a second saturable reactor in said one circuit for controlling the signal therein, a reactor in said other circuit and means for supplying saturating current therefrom to said second saturating reactor.
